Des. 194,675
Patented Feb. 26, 1963

194,675

CEILING TILE

Howard H. Vogel, Northbrook, Ill., assignor to The Celotex Corporation, Chicago, Ill., a corporation of Delaware

Continuation of design applications Ser. No. 65,015, May 3, 1961, and Ser. No. 65,016, May 3, 1961. This application July 5, 1962, Ser. No. 70,860

Term of patent 14 years

(Cl. D18—2)

Fig. 1

Fig. 2

Fig. 3

FIGURE 1 is a front face view of a ceiling tile, showing my new design;

FIGURE 2 is a cross-sectional view taken along line 2—2 of FIGURE 1; and

FIGURE 3 is a front face view of a modified form of the ceiling tile shown in FIGURE 1, wherein a grid pattern of perforations is superimposed upon the tile.

The characteristic features of my new design reside in the placement of the circular depressions of various sizes in combination with the tile, as shown.

This application is a continuation of my co-pending applications, Serial No. D. 65,015, filed May 3, 1961, and Serial No. D. 65,016, filed May 3, 1961 and now abandoned.

I claim:

The ornamental design for a ceiling tile, as shown and described.
